UNITED STATES PATENT OFFICE

RICHARD R. BLOSS, OF COLUMBUS, OHIO

METAL DRILLING-RIG STRUCTURE

Original application filed July 14, 1924, Serial No. 725,897. Divided and this application filed May 27, 1927. Serial No. 194,800.

My invention relates to a metal drilling rig structure and, more particularly, to the provision of a sand reel supporting structure that is adjustable to support different sand reels regardless of the length of the sand reel shaft.

In the use of drilling rig structures, the variations in the length of the sand reel shafts, whether or not the sand reel is equipped with a single friction pulley or a double friction pulley, has resulted in difficulties connected with the supplying of drilling rigs to the user. Obviously, the varying lengths of the sand reel shaft is not of such vital importance in wooden structures wherein the supporting structure may be readily altered, by cutting, upon the ground where the rig is to be assembled. However, such variations become of vital importance in metal drilling rig structures for the reason that metal parts cannot be readily cut to size upon the drilling rig site and, clearly, it would not be feasible to maintain a stock of various sized parts.

This application is a division of my copending application, Serial No. 725,897, filed July 14, 1924, steel drilling rig structure.

The primary object of my invention is to provide a sand reel supporting structure wherein the sand reel supports are adjustable in such a way that the sand reel may be adapted to any rig structure regardless of the length of the sand reel shaft or the number of friction pulleys mounted thereon.

Another object of my invention is to provide a bearing means for accommodating the varying lengths of sand reel shafts and for ensuring the proper alignment of such shafts.

Still another object of my invention is the provision of a sand reel supporting structure that may be adjusted both longitudinally and transversely of the rig in such a way that it may be readily adapted to any rig structure in the field, regardless of the length of the sand reel shaft, diameter of the sand reel friction pulley, diameter of the band wheel, or regardless of the number of pulleys mounted on the sand reel shaft.

Other objects of my invention will appear in the following detailed description and the preferred embodiment of my invention will

be seen in the accompanying drawings wherein similar characters of reference designate corresponding parts and wherein

Figure 1 is a front view of my sand reel structure showing the tail and knuckle posts mounted to accommodate a relatively long sand reel shaft.

Figure 2 is a view similar to Figure 1 showing the tail post, mounting and sill, moved inwardly along the sand reel sill to accommodate a shorter sand reel shaft than that shown in Figure 1.

Figure 3 is a view similar to Figure 2 showing the tail posts in the same position as in Figure 2 but showing the brake pulley removed and the manner of moving the knuckle post inwardly to accommodate shorter shafts.

Figure 4 is a view similar to Figure 3 showing the manner of rotating the swing lever 180 degrees about its own axis to accommodate various lengths of sand reel shafts.

Figure 5 is a perspective view of the bearing in which the ends of the sand reel shaft are disposed.

Figure 6 is a fragmentary view of the supporting structure for one end of the sand reel, including the tail post mounting and pivoted tail post and showing the manner of adjusting the tail post about said pivot.

Figure 7 is a fragmentary view of the swing lever and knuckle post structure for the end of the sand reel opposite to that shown in Figure 6 and showing the manner of oscillating the swing lever about the knuckle post pivot.

With reference to the drawings, I have shown a sand reel structure 1, preferably supported by means of a sill 2 extending transversely of the rig structure, a suitable tail sill 3 and a knuckle sill 4. The sills 3 and 4 extend longitudinally of the rig structure. The sand reel structure 1 comprises the shaft 5, a friction pulley 6 positioned adjacent one end of the shaft 5 and a spooling drum 7 positioned toward the other end of the shaft.

The sand reel may, if desired, be provided with a brake pulley 8 (see Figures 1 and 2), which latter pulley is preferably positioned between one end of the shaft 5 and the fric-

tion pulley 6, as shown in the figures. Power is designed to be transmitted to the sand reel by virtue of contact between the band wheel 9 and the friction pulley 6. The band wheel 9 is preferably driven by a belt 10 which is, in turn, driven by a suitable motor (not shown).

The ends of the sand reel shaft 5 are designed to be pivotally supported by means of swivel bearings 11 and 12 preferably constructed in the manner of the bearing shown in Figure 5. The swivel bearings 11 and 12 are provided with trunnions 13. The trunnions 13 of the bearing 11 fit in suitable angles carried by a swing lever 14 and the trunnions 13 of the bearing 12 fit in suitable angles carried by a tail post 15.

As shown in Figure 7, the swing lever 14 is pivoted as at 16 to the knuckle post 17 and, as shown in Figure 6, the tail post 15 is pivoted to the tail post mounting 18 as at 19. By mounting the swing lever in such manner, it will be clearly apparent that the swing lever 14, the swivel bearing 11 and one end of the shaft 5 may be oscillated as a unit about the pivot 16. The effect and purpose of swinging the swing lever 14 about the pivot 16 is illustrated in Figure 7 wherein the friction pulley 6 is shown in position to contact with the band wheel 9 and, in dotted lines, in contacting position with the back brake 20. It will also be clearly apparent that, by suitable adjustment of the turnbuckle braces 21 (see Figure 6), the tail post 15, the swivel bearing 12 and the end of the shaft 5 may be oscillated about the pivot 19.

The purpose of providing each end of the shaft 5 with swivel bearings is to permit the sand reel shaft to be moved forward or backward as a unit and to permit either end of the sand reel shaft to be independently adjusted in a plurality of directions without destroying the alignment of the shaft 5 with the bearings 11 and 12. In other words, as the knuckle and tail posts or their supporting members are adjusted, changing the direction of the action of the sand reel shaft, the bearings of the shaft are kept in proper relation to the sand reel by means of their swivel bearings.

The knuckle post 17 is adjustably secured to the sill 4 by suitable index holes and angles, as best shown in Figure 7, and the lower end of the knuckle post is adjustably secured in the same manner to the sand reel sill 2. The tail post 15 is adjustably secured to the sill 3 and the sand reel sill 2 in the same manner, as shown in Figures 1 to 4, inclusive. Thus, as is clearly indicated in the drawings, the tail post mounting and the knuckle post are adjustable longitudinally of the sills 3 and 4 and, at the same time, the entire structure is adjustable transversely along the sand reel sill 2.

In Figure 1, the knuckle post and tail post

mounting are shown positioned to accommodate a relatively long sand reel shaft. In Figure 2, the tail post mounting and tail sill 3 are shown adjusted inwardly along the sand reel sill 2 whereby the bearing 12 will accommodate a shorter shaft 5. In Figure 3, the tail post mounting and the tail post 3 are shown in the same position as in Figure 2 but the knuckle post 17 is shown moved inwardly along the sand reel sill 2 to accommodate a still shorter sand reel shaft.

A further adjustment of the swivel bearing 11 longitudinally of the sand reel shaft may be accomplished by turning the swing lever 14 180 degrees about its own longitudinal axis, which may be done by reversing the swing lever 14 on its pivot 16, as shown in Figures 3 and 4. This reversing of the swing lever is best illustrated in Figures 3 and 4 and the relative change in position of the bearing 11 is shown in these two figures whereby an additional means is provided for shortening or lengthening the distance between the sand reel shaft bearings 11 and 12.

By reference to the preceding description and the drawings attached hereto, it will be clearly seen that I have provided a rig structure which comprises means for adjusting the sand reel bearings longitudinally and singly or as a unit or transversely and independently of each other whereby such bearings will not only take care of the alignment of the friction pulleys and spooling drums but may be adjusted to accommodate various sizes of band wheels and, also, varying lengths of shafts.

Having thus described my invention, what I claim is:

1. Drilling rig structure comprising a knuckle post, an adjustably mounted tail post, an adjustably mounted swing lever, a sand reel shaft, swivel bearings mounted on said tail post and said swing lever for supporting said sand reel shaft and means for adjusting said swivel bearing into operative position on either side of said knuckle post.

2. Drilling rig structure comprising a knuckle post, a tail post, a sand reel shaft carried thereby, said knuckle post and said tail post being both adjustable as a unit and adjustable relative to each other.

In testimony whereof I hereby affix my signature.

RICHARD R. BLOSS.
